THERMALLY SENSITIVE CONTROL SWITCH

Samuel G. McPherson, Jr., Pueblo, Colo.

Application October 31, 1938, Serial No. 238,043

4 Claims. (Cl. 200—52)

This invention relates to improvements in thermally controlled switches and is particularly concerned with a new and improved control switch sensitive to variation both in temperature and humidity.

Control switches of the type heretofore used have been sensitive to variations in temperature or in humidity; it is an object of the present invention to provide a switch sensitive to variations both in humidity and in temperature whereby air conditioning apparatus including a heater, a cooler, and a humidifier can be substantially automatically controlled.

Another object of the present invention is to provide a new and improved psychrometrically controlled switch which can be adjusted to function for any preselected atmospheric temperatures and degrees of relative humidity.

Another object of the present invention is to provide a novel psychrometrically controlled switch of the type aforesaid which comprises relatively few parts, all of which are simple of construction and can be manufactured from relatively cheap materials, whereby manufacture of the device by mass production is at least largely promoted, and the necessity of repair because of breakdown during use is minimized.

An advantage of the novel switch according to the instant invention is the relatively few moving parts thereof which result in long, useful life of the device without necessity of replacing worn parts.

A noteworthy feature of the switch, according to this invention, is its simplicity of construction and the relatively small number of elements comprising the device whereby it is especially suited to the requirements of mass production.

Other objects, advantages and features of the novel psychrometrically controlled switch according to the present invention will be apparent to those skilled in the art during the course of the following description.

Regarded in certain of its broader aspects the present invention comprises a pair of mounted, thermally sensitive, elements arranged whereby variation in temperature of said elements results in movement of ends thereof in opposite direction, means whereby one of said elements is made sensitive to variations in humidity in addition to variations in temperature, a conductor member connected through said ends of said elements and movable therewith, and a series of electrical contact elements cooperating with said conductor whereby variations in atmospheric temperature and/or humidity result in establish-

ment of electrical connection, successively, between the conductor and said contact elements.

In order to facilitate a fuller and more complete understanding of the matter of the present invention, a specific embodiment thereof will be hereinafter described, it being clearly understood, however, that this specific embodiment is given solely by way of example and is non-limitative upon the scope of the present invention, except as is expressed in the subjoined claims.

Referring then to the drawing:

Figure 1 is substantially a front elevational view of the presently preferred embodiment of the instant invention, parts being broken away for clearness of illustration and the electrical circuits being shown in schematic form.

Figure 2 and Figure 3 are, respectively, front elevational views of the device illustrated in Figure 1 showing the electrical conductor elements thereof in different positions, the former showing the conductor in position of maximum slack, and the latter showing the conductor in substantially taut condition.

Referring now to the drawing it will be noted that the illustrated embodiment of this invention comprises a support 10 preferably a vertically positioned, essentially flat plate carrying a pair of projecting rotatable but normally frictionally held posts 11 and 12 upon which are mounted the thermally sensitive elements 13 and 14, substantially as shown. It is to be noted that the thermally sensitive elements 13 and 14 comprise spirally curved end portions 13a and 14a, respectively, the spirals being wound in opposite direction. It is to be understood that the thermally sensitive elements 13 and 14 are of any conventional type such as composite elements now commonly in use which comprise united members having different coefficients of expansion whereby variation in temperature of the structure results in distortion of the shape thereof. It is to be noted that the thermally sensitive element 14 is provided with a covering 14b of relatively absorbent material communicating by means of a wick 14c with a fluid reservoir 14d. In this manner evaporation of fluid from the coating 14b alters the temperature of the element 14 due to the absorption of heat by evaporation of fluid.

The distal free ends 13b and 14e of the thermally sensitive members 13 and 14 respectively carry, disposed in a catenary therebetween, an electrically conductive element 15, said element being formed of flexible material whereby movement of the free ends of the thermally sensitive

elements result in vertical motion of intermediate portions of said conductor element.

It will be apparent to those skilled in the art that the free end portion 13b of the element 13 will move, in the illustrated embodiment of the present invention, in a counterclockwise direction as the temperature rises, and conversely that the element 14 will operate whereby its free end portion 14e will move in a clockwise direction as the temperature thereof increases. It is to be noted that the motion of the end portion 14e of the element 14 is not dependent solely upon variation in temperature but instead upon variations both in temperature and humidity.

15 A pair of guide elements 16 and 17 mounted in spaced parallelism upon the support 10 by fastening means 18, define a vertically extending channel for slidably receiving a plate-like member 19 carrying contact elements 20, 21, and 22 thereon substantially as shown. It is to be noted that the member 19 is vertically adjustable by means including a rack 23 associated with said member and engaging with a pinion gear 24 whereby vertical motion can be imparted to said member 19 by rotation of said gear 24. It is particularly to be understood that the flexible electrical conductor 15, as it moves from relatively taut to relatively slack position wipes across, successively, the contact elements 20, 21, and 22 hereinbefore referred to.

In use of the device, electrical circuit is established including a power source 26 electrically connected to the conductor 15 and relay switches connected to said power source through means including the contact elements 20, 21, and 22, whereby said relays can be operated by wiping of the conductor member 15 across said contact elements. It is to be understood of course in this connection that insulation can be provided upon the device for electrically isolating the contact elements 20, 21, and 22, relative both to each other and to the wiping conductor member 15, these features being conventional in the art and not illustrated.

45 For a further understanding of the instant invention the figures of the drawing can be considered as illustrations of the relative position of elements of the device under different atmospheric conditions. For instance, in Figure 1 the catenary conductor is shown in an intermediate position in contact with the contact element 21. Under these conditions it may be assumed that the apparent variation in temperature between the elements 13 and 14 is five degrees C. That is to say, evaporation of moisture from the coating 14b of the member 14 results in lowering the temperature of said element by five degrees. Referring now to Figure 2 it will be noted that the catenary conductor 15 is illustrated in contact with the contact element 22, that is to say that the conductor is in the maximum slack position. This position corresponds to the maximum difference in apparent temperature of the thermally sensitive elements 13 and 14 which may be assumed in this instance to be 10 degrees. Another position of the catenary conductor 15 is illustrated in Figure 3 and corresponds to relatively taut condition of said conductor. It is to be noted that the conductor, when so disposed, is in contact with the contact element 20. It is particularly to be noted in respect to this figure that although the apparent temperature difference between the thermally sensitive elements 13 and 14 is but five degrees as was noted in regard to Figure 1 hereinbefore referred to, the temperature of each of

the thermally sensitive elements is increased by ten degrees, whereby the end parts 13b and 14e respectively of said elements, are disposed at the maximum distance from each other limited by the catenary conductor.

Having thus described the matter of the present invention, what is desired to secure by Letters Patent is expressed in the following claims.

I claim:

1. A psychrometrically controlled switch comprising a first and a second thermal-sensitive element arranged whereby, in use, moving ends of said elements travel in opposite directions; said second element carrying a moisture laden cover whereby variations in humidity alter the temperature of said element; an electrical conductor mounted on the moving ends of said elements; and a series of electrically isolated contact elements wiped by said conductor during motion of said end of said thermal-sensitive elements, whereby variations in surrounding atmospheric temperature and, upon occasion, humidity, cause said conductor to successively wipe the contact elements and establish electrical contact therewith.

2. A psychrometrically controlled switch comprising a first and second thermal-sensitive element arranged whereby, in use, moving ends of said elements travel in opposite directions; said second element carrying a moisture laden cover whereby variations in humidity alter the temperature of said element; an electrical conductor mounted on the moving ends of said elements; a vertical adjustable sliding plate, and a series of electrically isolated contact elements mounted on said plate and wiped by said conductor during motion of said ends of said thermal-sensitive elements whereby variations in surrounding atmospheric temperature and, upon occasion, humidity, cause said conductor to successively wipe said contact elements and establish electrical contact therewith.

3. A psychrometrically controlled switch comprising a support; a first and a second thermal-sensitive element mounted on said support; said first element being mounted at a place distal relative to one end thereof whereby variation in temperature of said element results in movement of said end; said second element being mounted similarly to said first element but in a manner whereby, in use, the moving ends of said elements travel in opposite directions; said second element carrying a moisture-laden cover whereby variations in humidity alter the temperature of said element; a flexible electrical conductor mounted on and disposed in a catenary between the moving ends of said first and said second elements; and a series of electrically isolated contact-elements wiped by said conductor during motion of said ends of said thermal-sensitive elements, whereby variations in surrounding atmospheric temperature and, upon occasion, humidity, cause said conductor to successively wipe said contact elements and establish electrical contact therewith.

4. A psychrometrically controlled switch comprising a support; a first and a second thermal-sensitive element mounted on said support; said first element being mounted at a place distal relative to one end thereof whereby variation in temperature of said element results in movement of said end; said second element being mounted similarly to said first element but in a manner whereby, in use, the moving ends of said elements travel in opposite directions; said second element

carrying a moisture-laden cover whereby variations in humidity alter the temperature of said element; a flexible electrical conductor mounted on and disposed in a catenary between the moving ends of said first and said second elements; a vertically adjustable sliding plate, and a series of electrically isolated contact-elements mounted on said plate and wiped by said conductor during

5 motion of said ends of said thermal-sensitive elements whereby variations in surrounding atmospheric temperature and, upon occasion, humidity, cause said conductor to successively wipe said contact elements and establish electrical contact 5 therewith.
